US00D835037S

(12) **United States Design Patent** (10) **Patent No.:** **US D835,037 S**
(45) **Date of Patent:** ** *Dec. 4, 2018

(54) **REMOTE BALLAST**

(71) Applicant: **HGCI, Inc.**, Las Vegas, NV (US)

(72) Inventor: **Christopher Reynolds**, Vancouver, WA (US)

(73) Assignee: **IP Holdings, LLC**, Vancouver, WA (US)

(*) Notice: This patent is subject to a terminal disclaimer.

(**) Term: **15 Years**

(21) Appl. No.: **29/593,783**

(22) Filed: **Feb. 13, 2017**

Related U.S. Application Data

(63) Continuation of application No. 29/527,564, filed on May 20, 2015, now Pat. No. Des. 780,691.

CLAIM

The ornamental design for a remote ballast, as shown and described.

DESCRIPTION

FIG. 1 is a perspective view of a remote ballast showing my new design;

FIG. 2 is another perspective view of the remote ballast shown in FIG. 1;

FIG. 3 is a front elevation view of the remote ballast shown in FIG. 1;

FIG. 4 is a rear elevation view of the remote ballast shown in FIG. 1;

FIG. 5 is a top plan view of the remote ballast shown in FIG. 1;

FIG. 6 is a bottom plan view of the remote ballast shown in FIG. 1;

FIG. 7 is a right side view of the remote ballast shown in FIG. 1;

FIG. 8 is a left side view of the remote ballast shown in FIG. 1; and,

FIG. 9 is an exploded perspective view of the remote ballast, as shown in FIG. 2.

The broken lines shown represent unclaimed subject matter and form no part of the claimed design.

1 Claim, 7 Drawing Sheets
